SUPPORT FOR BUNDLED CABLES

Clive R. Mackness, Sefton, New South Wales, Australia,
assignor to Dulmison (Australia) Pty. Limited, Sefton,
New South Wales, Australia

Filed Sept. 11, 1969, Ser. No. 19,101

Claims priority, application Australia Mar. 11, 1969

Term of patent 14 years

Int. Cl. D8—03

U.S. Cl. D8—230

FIG. 1 is a side elevational view of a support for bundled cables showing my new design;

FIG. 2 is an end elevational view thereof;

FIG. 3 is a top plan view thereof; and

FIG. 4 is a cross-sectional view on line 4—4 of FIG. 1.

I claim:

The ornamental design for support for bundled cables, as shown and described.
